POUCH FOR TOILET ARTICLES

Ella B. Blom, Jackson Heights, N. Y.

Application December 13, 1932
Serial No. 646,943

4 Claims. (Cl. 132—83)

This invention relates to a pouch for toilet articles.

The object of the invention is the production of a pouch for toilet articles of flexible material, 5 and which can be easily folded when not in use to fit a ladies' hand bag and the like.

The second object of the invention is the production of a pouch for toilet articles, which can be easily unfolded to simultaneously bring into 10 view and make accessible the mirror, powder compacts and powder puffs thereof.

The third object of the invention is the production of a pouch for toilet articles having detachably supported therein powder compacts and 15 powder puffs, with the latter bearing on the former when the pouch is not in use and in folded position.

The fourth object of the invention is the production of a pouch for toilet articles containing 20 a mirror, powder compacts and powder puffs which can be easily detached.

In the accompanying drawing Fig. 1 represents 25 a plan view partly broken away of an exemplification of the pouch for toilet articles, and in its open or extended position; Fig. 2 shows a section of Fig. 1 on the line 2, 2; Fig. 3 indicates a section on a reduced scale of Fig. 1 on the line 3, 3; Fig. 4 is a section on a reduced scale of Fig. 1 on the line 4, 4; Fig. 5 indicates a view similar to Fig. 1 30 of a modification of the pouch and Fig. 6 is a section of Fig. 5 on the line 6, 6.

The pouch for toilet articles in this exemplification is indicated to consist of the body portion 20 of fabric or other flexible material or various colors, having the longitudinal side edges 21, the top edge 23 and the bottom edge 24. The said body portion 20 is adapted to be folded on the dotted 35 lines 25 and 26.

To the inner face of the upper portion of the body portion 20 and at its side edges 21 and the top edge 23 is stitched the mirror holding member 29 having the lower edge 30, by means of the stitching 31. An oval opening 32 in this instance is indicated in the member 29. The said member 40 29 may be of the same material and the same color as the body portion 20. An upper pocket 33 is formed between the body portion 20 and the member 29. An inner holding flap 35 has its lower edge stitched to the lower edge 30 of the member 29 by the stitching 36. A mirror 38 is detachably positioned in the pocket 33 and is held in place by the holding flap 35.

At about the middle portion of the body portion 45 20 of the pouch is indicated the inner member 40 of flexible material, which may be of thin

material of the same color as the body portion 20, or of a different color. A cushion member 41, preferably of heavy material and generally of the same color as the body portion 20 is positioned upon the member 40. A cover 42 of stiff material, preferably celluloid and the like and having a pair of openings 43 is positioned over the member 41. The members 40, 41 and the cover 42 are stitched to each other and to the body portion 20, by means of the stitching 45, and the members 40, 41 and cover 42 are stitched to each other by the longitudinal central stitching 48 forming a pair of compact pockets 50. A pair of concaved compact holders are indicated at 52 with their powder compacts 53 and 54 which are preferably of different colors. The compact 53 may be red and the compact 54 may be white.

At the lower portion of the body portion 20 is indicated the inner member 57, which may be of thin flexible material of the same or different color as the body portion 20. A powder puff holding member 58 of flexible material similar to the body portion 20 and of the same or a different color or as the said body portion 20, having a pair of openings 59 is positioned over the inner member 57. The openings 59 are longitudinally in line with the openings 43. The members 57 and 58 are stitched at their top and side edges to the body portion 20 by the stitching 64. A longitudinal line of stitching 65 connects the members 57 and 58 to form a pair of powder puff pockets 66. A pair of powder puffs are each indicated having the circular body portion 70, with the operating loop 71. The said body portions 70 are detachably positioned between the members 57 and 58 axially in line with the openings 59.

The pouch indicated in Figs. 1 to 4 inclusive, when used is opened as shown best in Fig. 1, and the user withdraws one of the powder puffs having the body portion 70 from its pocket 66 by means of the operating loop 71 of the powder puff. The body portion 70 is then rubbed on its coating red powder compact 53. The same procedure may be followed with the other powder puff and the powder compact 54. The user rubs the powder puff on the face or other place where it is to be applied. When the user finishes using the pouch it is folded on the line 25 and the powder puffs having the circular body portions 70 are positioned to bear on the powder compacts 53 and 54. Next the compact is folded on the line 26 and the front face of the member 29 is positioned to bear on the rear face of the lower portion of the body portion 20. The fact that the powder puffs bear on the powder compacts

when the pouch is in its folded position may obviate the necessity of rubbing the powder puffs on the powder compacts, when said puffs are to be used.

5 Referring to Figs. 5 and 6 the modified pouch for toilet articles is again shown in its open or extended position. The modified pouch comprises the body portion indicated in its entirety by the numeral 80 and is of fabric or other flexible material, which may be of various colors. The said body portion 80 is divided into the top circular shaped member 81, the middle circular shaped member 82 and the lower circular shaped member 83. The members 81, 82 and 83 may 10 be folded on the dotted lines 86 and 85. A partial circular shaped mirror holding member 90 having the straight lower edge 91 is stitched to the member 81 for a portion of its circular edge by the circular row of stitches 96. A circular opening 97 is indicated in the member 90. The said member 90 may be of the same material and the same color as the body portion 80. An upper pocket 100 is formed between the members 81 and 90. An inner folding flap 101 has its lower edge 15 stitched to the lower edge 91 of the member 90 by the straight stitching 102. A circular shaped mirror 105 is detachably positioned in the pocket 100 and is held in place by the holding flap 101. Over the middle circular shaped member 82 is indicated the flexible inner member 108 having the straight upper edge 109 and the straight lower edge 110, and which may be of the same material and of the same color, as the body portion 80, or of a different color. A cushion member 115 20 having the straight upper edge 116 and the straight lower edge 117, preferably of heavy material and generally of the same color as the body portion 80 is positioned upon the member 108. A circular cover 120, preferably of celluloid or of other stiff material having the straight upper edge 121, the straight lower edge 122 and the circular opening 124 is positioned over the member 115. The members 108, 115 and the cover 120 25 are stitched to each other and to the member 82, by means of the stitching 126 and 127. A compact pocket is formed at 130 between the member 115 and the cover 120. A concaved compact holder 132 with its powder compact 133 is positioned in the pocket 130 with the powder compact extending through the opening 124.

Over the member 83 is indicated the inner member 140, having the straight upper edge 141 and straight lower edge 142. The member 140 30 may be of thin flexible material of the same or different color as the member 83. A holding member 145 with the straight upper edge 146, and the circular opening 147 is positioned over the member 140 and forms a powder puff pocket 149 therewith. The member 145 is of flexible material, which may be of the same color as the member 83, or of a different color. A powder puff 35 having the circular body portion 152 with the operating loop 153, is detachably positioned between the members 140 and 145. The members 83, 140 and 145 are connected by the stitching 155.

The pouch shown in Figs. 5 and 6 is used in a manner similar to that described for the pouch shown in Figs. 1 to 4. When the user finishes using this modified pouch it is folded on the lines 86 and 85 as described for the other form of pouch.

It will be noted that covers 42 and 120 being 40 of celluloid or other similar smooth stiff material can be easily cleaned. It is to be noted that the

pouch and its various parts can be made of various flexible materials such as leather, imitation leather, rubberized cloth, cretonne and of various other materials.

Various modifications may be made in the invention and the present exemplification is to be taken as illustrative and not limitative thereof.

Having described my invention I claim:

1. In a pouch for toilet articles the combination of a body portion of flexible material, a mirror holding member of flexible material having an opening and having its top and side edges fastened to the upper portion of said body portion at its inner face, said mirror holding member having its lower edge separated from said body portion, an inner folding flap positioned to the rear of said mirror holding member and having its lower edge fastened to the lower edge of said mirror holding member, a mirror detachably positioned between said mirror holding member and said flap, a compact holder carrying a powder compact detachably secured to said body portion at its face adjacent to said mirror holding member, and a powder puff detachably supported on said body portion adjacent to said compact holder and axially in line therewith, said body portion adapted to be folded to position, said powder puff upon said powder compact.

2. In a pouch for toilet articles the combination of a body portion of flexible material, an inner member of flexible material, bearing on the inner face of said body portion, a powder puff holding member of flexible material having an opening positioned over said inner member, the contours at the sides and top of both of said members fastened to said body portion, a powder puff detachably positioned between said members, at the said opening, a compact holder with a powder compact detachably supported on said body portion in line with said powder puff and a mirror detachably supported on said body portion in line with said powder puff and compact holder.

3. In a pouch for toilet articles the combination of a body portion of flexible material, an inner member of flexible material bearing against the inner face of said body portion, a cushion member bearing on the inner member, a cover of stiff material positioned over said cushion member and having an opening, said inner member, cushion member and cover connected to each other and said body portion at their sides and lower portions and separated from each other at their top portions, a compact holder with its powder compact detachably positioned between said cushion member and cover and opposite the opening in the latter, a mirror and a powder puff detachably connected to the said body portion and in line with each other.

4. In a pouch for toilet articles the combination of a body portion of flexible material, a mirror holding member with its top edge and side edges fastened to the upper portion of said body portion at its inner face, a holding flap positioned to the rear of the mirror holding member with its lower edge fastened to the lower edge of the mirror holding member, a mirror detachably positioned between the mirror holding member and said flap, a powder puff holding member of flexible material having a pair of openings, an inner member of flexible material to the rear of said powder puff holding member, both of the two latter members having the top and side edges fastened to lower portion of the pouch at its inner face, the powder puff holding member and its accompanying inner member fastened to each

other at their longitudinal central portions to form a pair of pockets, opposite the openings in said powder puff holding member, a powder puff detachably positioned in each of said pockets 5 opposite the pair of openings, an inner member of flexible material and a cushion member superimposed thereon, a cover of stiff material positioned over said cushion member, said cover having a pair of openings therein, said latter inner 10 member, the cushion member and the cover connected to each other at their central longitudinal

portions to form a pair of pockets, said latter inner member, cushion member and cover fastened to said body portion at its inner face at their bottom and side edges, in about the middle portion of the body portion, and a compact holder with its powder compact detachably positioned in each of the latter pockets with the powder compacts partially extending through the openings of said cover. 80
